MILLING MACHINE

Fred A. Hassman, Cincinnati, Ohio, assignor to
The Cincinnati Milling Machine Co., Cincinnati,
Ohio, a corporation of Ohio

Application April 3, 1941, Serial No. 386,695

10 Claims. (Cl. 90—21)

This invention relates to milling machines and more particularly to improvements in transmission and control mechanism therefor.

In certain types of milling machines and especially in the smaller sizes the variable feed gear box is mounted in the knee, the spindle transmission and the motor are mounted in the column, and a common start and stop control clutch is provided in the column for simultaneously connecting or disconnecting both transmissions to or from the prime mover. An extensible power train transmits motion at a constant rate from the column to the knee and means are provided in the knee for serially connecting this train with the feed box for operation of the work support units at a feed rate or selectively connecting the train direct to the units for rapid traverse operation. Since the feed-rapid traverse selector is located in the knee it should now be obvious that when the main clutch is disconnected no power is available in the knee for rapid traverse adjustment of the various work support units for setup purposes and such adjustments must, therefore, be effected manually.

It is an object of this invention to improve the construction of such machines whereby, even although the main clutch is disengaged, power is available in the knee for rapid traverse purposes only.

Another object of this invention is to obtain these results with a minimum addition of mechanism because of the limited space available in such machines and their general compact nature.

A further object of this invention is to generally improve the operation of milling machines of the type described herein.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a side elevation of a milling machine embodying the principles of this invention.

Figure 2 is an expanded view of the variable speed transmission for the spindle of the machine.

Figure 3 is a partially expanded view of a portion of the transmission and control mechanism

in the knee as viewed on the line 3—3 of Figure 1.

Figure 4 is a detail vertical section on the line 4—4 of Figure 1.

Figure 5 is a horizontal detail section on the line 5—5 of Figure 1.

Figure 6 is a section on the line 6—6 of Figure 3.

Figure 7 is a detailed section on the line 7—7 of Figure 3.

Figure 8 is a diagrammatic view of the hydraulic control circuit.

Figure 9 is a detailed section on the line 9—9 of Figure 3.

Referring to Figure 1 of the drawings, the reference numeral 10 indicates the column of a knee and column type milling machine, the column having guide ways 11 on the front wall for receiving a vertically movable knee 12, the knee carrying a saddle 13 for cross movement, and the saddle in turn carrying a work table 14.

The column has a gooseneck portion 15 terminating in a vertically adjustable support 16 for a tool spindle 17. The work supporting table 14 thus has three directions of movement, one of which is parallel to the axis of adjustment of the spindle, whereby relative movement between the table and the cutter may be obtained by adjustment of the knee or adjustment of the spindle support.

The variable speed transmission for the spindle, shown in expanded view in Figure 2, is mounted in the column of the machine, while the feed box 18 for determining the rate of movement of the work supporting units, such as the table, saddle and knee is mounted on the side of the knee as shown in Figure 1.

Both of these transmission units derive their power from a common prime mover, such as the motor 19, which is enclosed in a housing 20 forming part of the column as shown in Figure 1. A common start and stop control clutch 21 shown in Figure 2 serves to simultaneously connect the motor 19 for actuation of the feed and speed transmissions. In other words, the motor 19 has a pinion 22 which continuously drives a gear 23, and the gear 23 continuously rotates one-half of the plates of the multiple disc clutch 21.

The remaining plates are operatively connected to a common drive gear 24 while the shifter spool 25 serves to effect frictional engagement between the plates for driving purposes. The shifter spool 25 is operatively connected through mechanism not shown to a manual con-

trol lever 26 mounted on the side of the column for manual control thereby.

The gear 24 functions as a common drive gear for the feed and spindle transmissions of the machine. The gear 24 is connected for rotation of the variable speed transmission through the following reversing means. A gear 27 slidably mounted on a splined shaft 28 intermeshes directly with the gear 24 for rotation of the spindle in one direction, and when shifted to the left out of engagement with the gear 24 and into engagement with idler gear 29, which has a second integral idler gear 30 continuously intermeshing with the gear 24, it effects rotation of the spindle in an opposite direction. The gear 27 thus serves as a reversing gear for the spindle.

The variable speed transmission comprises a spline shaft 28 which carries a shiftable unit 31 comprising gears 32, 33 and 34 that are adapted to be selectively intermeshed with gears 35, 36 and 37 respectively, fixed to shaft 33. A third shaft 29 has a first shiftable couplet 40, comprising gears 41 and 42, which is alternately shiftable to effect engagement of its gears with gears 35 and 36 respectively.

By means of this combination the shaft 39 may be driven at any one of six different speeds. The shaft 39 also has a second couplet 44 splined thereon comprising gears 45 and 46 which may be alternately intermeshed with gears 47 and 48 respectively, carried by the shaft 49. The shaft 49 is interconnected by bevel gearing 50 for rotation of the spindle 11. Thus, the spindle may be driven at any one of twelve different speeds and in opposite directions.

The gear 24 is operatively connected for operation of the work support units through the following transmission. This transmission includes first an extensible power train which extends to the knee and comprises a gear 51 which is in permanent mesh with the common drive gear 24 and operatively connected through an overrunning clutch 52 for rotation of a shaft 53 which terminates in a bevel gear 54. Referring to Figure 4 this bevel gear is connected to a bevel gear 55 fixed to the upper end of a vertical drive shaft 56 by means of intermediate bevel gears 57 and 58 attached to opposite ends of a shaft 59. The shaft 59 is a square shaft as shown in Figure 5 whereby it functions as a spline shaft and is vertically slidable through a gear 60 which as shown in Figure 6 is mounted against axial movement in the knee 12. This forms an extensible driving connection between the transmission in the column and the transmission in the vertically movable knee.

The gear 60 intermeshes with a gear 61 for driving a common reversing mechanism for the work support units indicated generally by the reference numeral 62. This mechanism includes a spline shaft 63 to one end of which the gear 61 is attached and upon which is slidably splined a shiftable reversing clutch 64. A pair of bevel gears 65 and 66 is supported for free rotation on the shaft 63 and are operatively connected to the shaft by the clutch member 64 for opposite rotation of a bevel gear 67 secured to the end of a drive shaft 68. The shaft 69 constitutes the input drive shaft for reversible actuation of the feed box and this box has a final output gear 69.

A gear 70 is shiftable into mesh with gear 69 for driving the work support units at feed rates, the gear 70 forming part of a gear train comprising gear 71 for vertical actuation of the knee through beveled gear 72, gear 73 for driving the

splined shaft 74 which is operatively connected for translation of the table and gear 75 which meshes with gear 76 for rotation of the saddle feed screw 78. Selector clutches 77 and 78 serve to determine actuation of the knee and saddle respectively. A start and stop clutch for the table is also provided but not shown. It will be noted that the clutches for the saddle and knee are also simple start and stop clutches, the reverser shown in Figure 6 acting as a common reverser for changing the direction of movement of all of the supports.

When it is desired to move the various work support units at a rapid traverse rate the input shaft 68 which runs at a constant rate is connected to the various support actuating gears 71, 75 and 73 independent of the feed box. This is accomplished in the following manner. A gear 79 integral with gear 67 drives through an idler gear 80, a gear 81 of a rapid traverse clutch 82. This clutch, as shown in Figure 3, is mounted on the table drive shaft 74 and a clutch shifter 83 is provided for effecting engagement of the clutch which is of the multiple disc type, one set of plates being connected to the gear 81 and the other set operatively connected to the gear 73. Since the gear 73 is splined on the shaft 74, engagement of the clutch 82 effects rotation of the gear 73 and connected train 79, 71, and 75 as well as shaft 74.

When the clutch is engaged, however, the gear 70 must be out of engagement with the gear 69 so that it can act as an idler gear to transmit motion from the gear 73 to the gears 71 and 75. Thus, the table drive gear 73, the knee drive gear 71 and the saddle drive gear 75 are now all rotated at a fast rate whereby operation of any of the supports at rapid traverse may be obtained, the direction still being controlled by the common reverser clutch shown in Figure 6. It will be noted that regardless of the position of the various control parts in the knee as just described there will be no power available for actuation of the work support units at either a feed rate or at a rapid traverse rate if the main clutch 21 is disengaged. By means of this invention a power connection is provided whereby power is made available in the knee when the rapid traverse clutch is engaged and is not available when the clutch is disengaged whereby when the spindle is stopped the work support units may be power shifted only at a rapid traverse rate.

The shifting of the rapid traverse clutch, as well as of the gear 73 is controlled by a manually operable lever 84 which is mounted on the side 55 of the knee for rotation of a shaft 85. This shaft is connected through the linkage shown in Figure 9 for axial shifting of a shifter rod 86. This linkage comprises a crank arm 87 secured to the shaft 85 and a link 88 which pivotally connects the crank to a block 89 secured to the rod 86. The angle of the crank arm is such that counterclockwise rotation of the crank 87 will effect shifting of the rod 86 to the left as viewed in Figures 3 and 9. A spring 90 is interposed between a fixed part of the knee and a collar 91 secured to the rod 86 for the purpose of holding the shifter rod in a feed position.

The end of the rod is provided with a shifter fork 92 which is operatively connected for shifting the gear 70. As shown in Figure 7, the shifter rod 86 has a rack and pinion connection 93 with a rotatable shaft 94 which at the other end has a rack and pinion connection 95 with a shifter rod 96 for the rapid traverse clutch shifter 83.

The shifter 83 has a lost motion connection with the rod 96. A spring 97 is interposed between the shifter and a fixed part of the knee for holding the shifter and clutch in a disengaged position. The rod 96 is provided with a collar 98 which is spaced from the shifter a definite amount to provide a limited lost motion to insure that the gear 79 is disengaged from the output feed gear 69 before the rapid traverse clutch is engaged. This insures against any attempt to drive the gear 79 at two different rates simultaneously which might cause damage to the transmission.

The rod 96 also carries a ball-ended lever 98 which fits into a slot 99 in a rotatable member 100. As shown in Figure 1, the shaft 53 is surrounded and protected by a series of telescoping tubes indicated generally by the reference numeral 101 whereby they may expand or collapse in accordance with upward or downward movement of the knee. These tubes have been provided with splines and the lower tube 102 is connected by a key 103 to the rotatable member 100 as shown in Figure 6. Thus upon rotation of the member 100 the rotary motion will be transmitted through all the tubes to a gear 104 which has a splined connection with the upper tube 105 as shown in Figure 4.

Referring to Figure 5 the gear 106 intermeshes with a rack bar 106 which has a spool valve 107 formed on the end thereof. The valve spool slides in a bore 108 in which there are formed two ports 109 and 110, Figure 3. A third port 111 is connected by channel means 112 to the output of a gear pump 113 which as shown in Figure 2 has a drive gear 114 intermeshing with the continuously driven gear 23. The pump has an intake 115 through which oil is withdrawn from a suitably located reservoir 116 located in the column. Thus, the port 111 constitutes a pressure port. The valve spool has an annular groove 117 for connecting the port 111 to the port 109 when the table transmission is connected for providing feeding rates. The port 109 is connected by a channel 118 to port 119 located in the end of a cylinder 120. A port 110 is connected by a channel 121 to a port 122 located in the end of cylinder 123. As shown in Figure 2, these cylinders support opposite ends of a shifter rod 124 upon which is mounted a shifter fork 125 for actuating a clutch 126 which serves to connect a gear 127 which is continuously driven by the gear 23 to the shaft 53.

It will be noted as stated supra that the gear 51 was connected by an overrunning clutch 52 to the shaft 53 and therefore when the gear 51 is not rotating due to disengagement of the clutch 21 the gear 127 may rotate the shaft 53 without causing rotation of the gear 51. It, therefore, follows that when the rapid traverse clutch lever 84 on the knee is actuated it rotates the gear 104 in a clockwise direction, shifting the spool valve 107, interconnecting the port 111 with the port 110 to effect engagement of the clutch 126 and at the same time the port 109 is connected to the annular groove 128 in the clutch spool which groove is interconnected by interdrilling 129 to the open end of the bore 108 whereby the cylinder 120 is connected to reservoir to permit the shifting. Thus the rapid traverse lever 84 effects disengagement of the gear 79 from the output feed gear 69, effects engagement of the rapid traverse clutch 82, shifts the valve spool 107 and thereby through the hydraulic connections effects engagement of auxiliary clutch 126 to

bypass the disconnected clutch 21 and provide power for rapid traversing the various work support units.

What is claimed is:

5. 1. In a machine tool having a fixed support, a movable support and a drive shaft extending from the fixed support to the movable support for translating the latter, the combination of a source of power located in the fixed support, a manual control mounted on the movable support, a telescoping tube surrounding and protecting said drive shaft, and motion transmitting connections including said tube extending from the manual control to the fixed support for connecting said source of power for operation of the drive shaft.
10. 2. In a machine tool having a fixed support, a movable support and a transmission shaft extending from the fixed support to the movable support, the combination of a power driven shaft mounted in the fixed support, a telescoping tube surrounding and protecting said transmission shaft, means mounted in the fixed support for operatively connecting said power shaft for actuation of said transmission shaft, a control lever mounted on the movable support and motion transmitting connections from said lever and including said telescoping tube for effecting operation of said means in the fixed support.
15. 3. In a machine tool having a fixed support, a movable support, a transmission shaft extending from the fixed support to the movable support, the combination with a prime mover mounted in the fixed support, of a first clutch for connecting said prime mover to the shaft, a second clutch for connecting said prime mover to the shaft, means mounted in the fixed support for effecting operation of one of said clutches, tubular means surrounding and protecting said shaft, a control lever mounted on the movable support and motion transmitting means including said tube for connecting said lever for operation of said second clutch.
20. 4. In a milling machine having a column, a knee adjustably mounted on the column, and work supporting slides mounted on the knee, the combination of a prime mover mounted in the column, a transmission shaft extending from the column to the knee, the telescoping tube enclosing and protecting said shaft, a first clutch mounted in the column, a control lever mounted in the column for operating said clutch to effect connection of the prime mover to said shaft, a second clutch mounted in the column for connecting the prime mover to said shaft, a control lever mounted on the knee, and motion transmitting connections between the last-named lever and said second clutch and including said tube.
25. 5. In a milling machine having a column, a knee slidably mounted on the column and work supporting slides mounted on the knee, the combination of a prime mover mounted on the column, a transmission shaft extending from the column to the knee for imparting movement to the knee and slides, a pair of clutches mounted in the column and arranged in parallel between said prime mover and said shaft, means carried by the column for operating one of said clutches, means carried by the knee for operating the other of said clutches, and an overrunning clutch mechanism interconnecting the output of said parallel clutches to said shaft whereby the shaft will be operated when either of said clutches is engaged.
30. 6. In a milling machine having a column and

a shiftable work support mounted on the column, the combination of a prime mover mounted in the column, a drive shaft extending from the column to the shiftable support for actuation thereof, a telescoping tube surrounding and protecting said shaft, a clutch mounted in the column for connecting said prime mover to the shaft, fluid operable means for shifting said clutch including a control valve mounted in the column, a control lever carried by the shiftable support, and motion transmitting means including said telescoping tube for controlling operation of said valve by said control lever.

7. In a knee and column type milling machine having a spindle rotatably journaled in the column and a knee, saddle and table supported on the column for relative movement with respect to said spindle, the combination of transmission means for the knee, saddle and table including a power driven shaft journaled in the knee and adapted to be driven at a constant speed, a feed box mounted in the knee having an input member connected to said shaft and a variably driven output member, a gear train including actuators for the respective supports, said gear train including a shiftable gear which is movable into and out of engagement with the output member of said gear box, a clutch for connecting another gear of said train to said input shaft, means including a manual control lever for controlling the shifting of the shiftable gear and the engagement and disengagement of said clutch, said control means including a lost motion connection whereby said gear will be disengaged before the clutch is engaged for actuation of the actuators at a fast rate, and said clutch will be disengaged before the shiftable gear is engaged for actuation of the actuators at a feed rate.

8. In a knee and column type milling machine having a column, a cutter spindle journaled in the column and a knee, saddle and table mounted on the column for relative movement with respect to said spindle, the combination of transmission and control means for the movable parts including a prime mover, a control clutch and a transmission serially arranged in the column for actuating the spindle, a transmission train having one end operatively connected to the prime mover through said clutch and the other end terminating in the knee, a rapid traverse gear and a feed gear driven by said train, individual actuators for the various supports, a shiftable gear for simultaneously connecting said actuators to said feed gear, a clutch

for simultaneously connecting said actuators to said rapid traverse gear, control means for alternatively effecting engagement with said feed gear and said rapid traverse gear for selective actuation of the parts at feed or rapid traverse rates, an auxiliary clutch mounted in the column for connecting the prime mover for actuation of said train when the main clutch is disengaged and control connections from the knee for effecting engagement of said auxiliary clutch only when said rapid traverse clutch is engaged whereby the knee, saddle and table may be actuated at a rapid traverse rate when the spindle is stopped.

13. In a machine tool having a tool support, a knee, saddle and table mounted on said support and a prime mover mounted in the support, the combination of means for actuating the knee, saddle and table including a variable feed gear box mounted in the knee and having an input shaft and an output gear, a shiftable gear normally held in engagement with said output gear, a clutch for operatively connecting said input shaft to said shiftable gear, means normally maintaining said clutch in a disengaged position, a manually operable shifter, means directly connecting said shifter to the shiftable gear and a lost motion connection between said shifter and clutch whereby said gear and clutch will be operated sequentially to insure disengagement of said gear before actuation thereof by said clutch.

10. In a milling machine having a column, a knee, saddle and table mounted on said column, a cutter spindle and prime mover mounted in the column, the combination of means for driving the knee, saddle and table including a variable feed gear box mounted in the knee and having an input shaft and an output gear, means to selectively connect the output gear to the knee, saddle and table for feeding purposes, means for connecting said input shaft to the knee, saddle and table for rapid traverse purposes, a clutch mounted in the column for connecting the prime mover for actuation of the spindle and said input shaft simultaneously for feeding purposes whereby when said clutch is disengaged the input shaft stops, a feed rapid traverse selector control lever mounted on the knee, and means operable by said lever when thrown to a rapid traverse position to effect connection of the prime mover to the input shaft and independently of said spindle.
